UNITED STATES PATENT OFFICE

LE VERN B. WISE, OF SUMMERSVILLE, PENNSYLVANIA

FOLDING CRATE

Application filed December 17, 1929. Serial No. 414,757.

This invention has reference generally to shipping containers and more particularly to a fruit container or crate which can be easily folded, when empty, so that a large number 5 can be shipped in a small crate and with the smallest possible shipping expense.

A further object is to provide a strong, compact structure which will withstand rough handling and at the same time adequately protect the fruit contents.

With the above objects in view, the invention consists of the novel construction, arrangement, and combination of parts hereinafter more fully described with reference 15 to the accompanying drawings, wherein:

Figure 1 is a front view of the crate in set up or shipping position,

Figure 2 is a horizontal section on line 2—2 of Figure 1,

20 Figure 3 is a vertical sectional view on line 3—3 of Figure 1,

Figure 4 is a bottom view of the crate in folded or collapsed position, and

25 Figure 5 is a sectional view of the folded crate.

The front A, back B, and sides or ends C and D, of the crates are preferably of slatted construction, while the top E and the bottom F are formed of imperforate panel members.

30 In assembling the units of the crate, the bars of slats 1 of the side members C and D have their forward ends inserted between the bars 2 of the front member A at opposite ends of the latter and pivotally connected to 35 the ends of the front bars 2 by a long rod 3 or other pivot means suitable for the purpose in view.

The rear end of the bars 1 are inserted 40 loosely between the bars 4 of the back member B and are suitably fastened, as at 5 within a reinforcing channel iron 6 which serves to strengthen as well as to connect the ends of the side bars for preventing the displacement of the back member.

45 Similar reinforcing irons are employed to connect the ends of the bars of the back member, as shown at 7 and 8, and to reinforce the edges of the bottom panel as shown at 9.

The front, back and side members are constructed with an equal number of bars but are

so connected that the bars of the side members overlap and are supported on the bars of the front and back members.

The topmost bar of the back member B has secured thereto a forwardly projecting and 55 longitudinally extending grip 10 of a width approximating or slightly exceeding the combined thickness of the front and bottom members A and B respectively. This strip has its surface flush with the upper face of 60 the topmost slat or bar and to the forward edge of the strip is connected, by a loose hinge connection 11, the panel top E.

The panel bottom F is connected directly 65 to the two lowermost bars of the back member by a loose hinge connection 12 which spaces the bottom member from the back member a distance exceeding a thickness of the front member only.

In the shifting or set up position of the 70 crate, the free end of the panel top is supported on the topmost bar of the front member which bar is cut out as shown at 13 to permit the top member to lie flush with the surface of the bar, and the free end of the 75 panel bottom is supported on the lowermost bar of the front member.

When the crate is filled, the weight of the 80 contents will fold down the panel bottom and the latter is provided near its free edge with a depending lug or abutment lip presenting a flat side bearing against the lowermost bar of the front member to hold the same in position; the panel bottom being 85 much smaller in thickness than the width of the space between the front bars 2 so that it has sufficient vertical play between the bars to raise the lug clear of the lowermost bar, preparatory to folding the crate.

The top E has a hingedly anchored hasp 90 15 which engages over a staple 16 on one of the front bars 2 to permit the top to be sealed by a padlock.

To fold the crate from a set up position, 95 the same is first turned to rest upon the front member A and the side members are grasped at the ends 6 and lifted; the hinge bottom member F being pushed in, if necessary, to disengage the lug 14 from the front member A which is lifted upwardly with the side 100

members and against the inner face of the back member.

The back member is upheld by the hinged top and bottom members during the lifting 5 of the front and side members and the weight of the top members upon the top and bottom members causes the latter to fold up under the back member when the latter is lowered by the reverse or downward movement of the 10 sides and front members, so that the parts are eventually folded in the manner shown in Figure 4, with the front member confined between the back and bottom members and the bottom member confined between the front 15 and top members; the side members being disposed in relatively overlapping engagement above the back member.

It will thus be seen that the inventor provides an improved foldable crate which 20 can be cheaply constructed of wood and metal or other material, if desired and which can be folded into a compact form, making possible the packing and storing of a considerable number of empty crates within a 25 small space.

Although the foregoing has reference to a crate of slatted construction, it will be understood that the invention is susceptible of being applied also to a crate in which the 30 crate forming units are composed of solid rather than slotted members.

Having thus described my invention, what I claim as new is:

1. A foldable crate comprising a back-forming unit, a top-forming unit carried by the back-forming unit, a bottom-forming unit also carried by said back-forming unit, a front-forming unit upon which the free ends of the said top and bottom-forming units 35 are respectively supported, said front-forming units being slideable inwardly along the top and bottom-forming units for disposal against the back-forming unit in the folded position of the crate and said top and bottom-forming units being respectively hinged to the back-forming units so as to bring inwardly in relatively overlapping relation for confining the said front-forming units between the back-forming units and the overlapping 40 top and bottom units, means carried by the said top and bottom forming units for engaging and retaining the said front units in place when the crate is in set up position, and side forming units slideable through the said 45 back-forming units and pivotally connected to the said front-forming units, said back and side-forming units being respectively provided with mutual abutment portions preventing disconnection of the units.
2. A foldable crate having a front, back and side units formed of slotted construction and relatively disposed with the bars of the side units inserted at their forward ends between and pivotally connected to adjacent 55 ends of the bars of the front units and having

their rear ends inserted loosely between the adjacent ends of the bars of the back units, a reinforcing member connecting the rear ends of the bars of each unit, a bottom-forming panel hingedly connected to a bottom bar of the said back unit with its free end normally adapted to be supported on the lowermost bar of the front unit, abutment means on said panel for engaging said lowermost bar, and a top-forming panel hingedly connected to a topmost bar of the said back unit and adapted to be normally supported at its free end upon the topmost bar of the front unit, said bottom panel being faced outwardly from the back unit so as to be foldable over the front unit for confining same between the back and bottom units in the folded position of the parts, and said top panels being spaced outwardly from said back units so as to be foldable over the said bottom panel.

In testimony whereof I affix my signature.
